(57) **CLAIM**

The ornamental design of an illumination apparatus, as shown and described.

DESCRIPTION

FIG. 1 is a perspective view of the illumination apparatus according to the present invention;

FIG. 2 is a top perspective view of an end segment of FIG. 1;

FIG. 3 is a perspective view of one end segment of FIG. 1; FIG. 4 is a perspective view of an opposite end segment of FIG. 1; and,

FIGS. 5 and 6 comprise a front perspective view of the illumination apparatus of FIG. 1.

The illumination apparatus is being shown broken away in FIGS. 2 through 6 for convenience of illustration.
